FIRE EXTINGUISHING PISTOLS

Harold Hutchinson, Acton, London, England

Application May 13, 1954, Serial No. 429,643

6 Claims. (Cl. 169—1)

This invention relates to fire extinguishing pistols of the kind wherein a cartridge containing a fire extinguishing compound or composition is fitted into a barrel which may be detachable from the butt of the pistol for recharging and wherein a spring propelled striker is released by the operation of trigger mechanism to detonate an explosive charge and eject the contents of the cartridge onto a fire.

Experience in the manufacture and use of fire extinguishing pistols of the kind above described has shown that their range tends to be limited by the tendency of the extinguishing mixture to become banked up or compressed thereby increasing the resistance to the action of the propellant gases. It has also been found that the full pressure of the explosive gases cannot always be utilised and that these gases tend to escape around the outer surfaces of the extinguishing mixture causing ineffective discharge thereof.

The object of the present invention is to provide improvements in the known construction of fire extinguishing pistols designed to overcome the difficulties described in the preceding paragraph; to ensure the effective sealing of the cartridge under all conditions; to protect the cartridge against deterioration; and to ensure the effective discharge of the cartridge irrespective of climatic conditions, or the effects of heavy handling or vibration.

According to the invention a fire extinguishing pistol of the kind above described is characterised by the provision of means for sealing both ends of the barrel, said means including a bushing at the rear end of the barrel adapted in conjunction with the firing pin to prevent escape of propellant gases and a double swaging at the muzzle end of the barrel to ensure fluid tight engagement with a sealing element.

In carrying the invention into effect it may conveniently be applied to a pistol having trigger and striker mechanism as described in the specification of my prior Patent No. 1,861,533 but the invention is not limited in that respect as any other mechanism capable of impelling a striker towards the centre of the rear end of the pistol barrel may be employed.

Reference will now be made to the accompanying drawings wherein:

Fig. 1 is a sectional elevation of the handle and butt portions of the pistol.

Fig. 2 is a sectional elevation of the barrel.

Figs. 3 and 4 are respectively face and edge views of a wad or disc for directing the propellant gases to discharge the fire extinguishing material.

The fire extinguishing pistol illustrated includes a sheet metal casing 1 the lower portion of which is formed as a handle 2. Within the casing is mounted a two-armed lever movable about a fixed pivot 3. One arm 4 of the said lever is formed integral with a striker 5 and its end 6 projects through a slot 7 in the casing and is shaped to facilitate manual operation to cock the pistol as herein-after described. The second arm 8 of the lever is connected to a spring 9 whose other end is anchored at 10

2

within the handle 2. Also mounted within the handle 2 is a trigger 11 movable about a fixed pivot 12 against the resistance of a spring 13. For convenience in manufacture and assembly the casing including the handle is formed in two parts secured together by rivets or the like at the points 14.

Adjacent the arm 4 of the lever the casing is secured to a cylindrical butt cap 15 in which the rear end of the barrel 16 is adapted to be detachably mounted. The barrel 16 consists of a metal tube whose rear end is secured into an end cap 17 of cylindrical form closed at its rear end which is formed with a central aperture 18. The end cap 17 carries projecting studs 19 adapted to engage in bayonet slots 20 to secure the barrel in position in the butt cap 15 which is also formed with a central aperture 21. Fixed into the aperture 21 is a bushing 22 having a central aperture through which passes a pin 23 which provides a substantially gas tight closure in the bush between the firing mechanism and the detonator of the cartridge and which projects through the aperture 18 at the rear end of the barrel and at the opposite end is provided with a head 24 with which the striker 5 makes contact when the pistol is operated. The arrangement above described is operated in the known manner by rocking the lever arm 4 to the position shown in broken lines in Fig. 1 whereby its end 8 rocks the trigger 11 to the cocked position. Thereafter, a pull exerted on the trigger 11 to rock it in a clockwise direction releases the lever 4—8 and enables the spring 9 to return it to the full line position shown in Fig. 1. This movement results in the striker 5 making a sharp impact on the head 24 of the pin 23 which is thereby caused to strike the percussion cap 29 and detonate the charge 30 held in a wad 31 to propel the cartridge from the barrel onto the flames which are to be extinguished. The use of the bushing 22 and the transmission of the impulse to detonate the propellant charge through the pin 23 seals the rear end of the barrel to prevent leakage and ensure that substantially the entire pressure developed by the detonation of the charge is utilised to propel the cartridge from the barrel.

In order to seal the muzzle end of the barrel to prevent deterioration of the fire extinguishing compound during storage, the arrangements shown in Fig. 2 are employed. To retain the sealing element securely in position, the muzzle end of the barrel is formed with a double swaging at 25 and 26. Into the annular recess formed by the swaging at 26 is formed the sealing member 27 which is of composite form consisting of a compound of high melting point bitumen held between two discs of card being preferably covered with a coating of tin or lead foil, and afterwards covered with a coating of paint. The compound for the sealing member is pre-heated to liquid form and poured over the disc which rests on the inward swaging at 25 until the compound is built up to the depth of, and fills swaging 26, the mouth of the barrel having been pre-heated to a higher temperature than that of the liquid compound to ensure the marrying or adhesion of the plastic compound to the metal of the cylinder, thereby effecting a complete air tight seal which is only broken by the full pressure created by the explosion of the propellant charge. Compression of the extinguishing mixture and consequent resistance to the action of the propellant gases is prevented by the introduction into the cartridge of a compressible and non-caking cushion 32 consisting of a powder of which kieselguhr is a suitable example. This powder acts normally as an elastic cushion to prevent the extinguishing mixture 33 settling through excessive and continuous vibrations but during the discharge operation it acts as an expansion chamber for the propellant gases owing to its greater compressibility than the extinguishing mixture, thereby acting as a

spring or cushion for the propellant gases enabling the initial impulse to be imparted to the extinguishing mixture in a progressive manner.

As a further aid to effective discharge the invention provides a wad or disc 28 of asbestos sheet disposed between the propellant charge 30 and the extinguishing mixture 33. This disc is provided centrally with a number of radial slots as shown in Fig. 3 initially closed but opened by the pressure of the propellant gases. The central disposition of the slots ensures even and central pressure being exerted on the extinguishing mixture and thus reduces or prevents the tendency of the propellant gases to escape around the outer surfaces of the extinguishing mixture. After use, the barrel 16 is removed for re-charging with a fresh cartridge and re-sealing.

I claim:

1. In a fire extinguishing pistol having means for ejecting a dry powder fire extinguisher, the combination of a firing pin for detonating a propellant charge, a striker adapted to engage and operate the firing pin, a barrel to enclose a cartridge containing the fire extinguishing powder, a propellant charge and a detonator therefor, a bushing extending from the rear end of the barrel through which the firing pin passes and arranged to seal the rear end of the barrel to prevent rearward release of pressure created by explosion of the propellant charge, a double swaging at the muzzle end of the barrel, and a sealing element having a fluid tight engagement with said swaging to prevent deterioration of the fire extinguishing powder.

2. A fire extinguishing pistol as defined in claim 1, including a butt cap in which the rear end of the barrel is engageable detachably, and wherein said bushing is cylindrical and located at the centre of the butt cap, the firing pin is longer than and passes through said bushing into the rear end of the barrel and forms a substantially gas tight closure of the bushing, said detonator is a percussion cap on the rear end of the cartridge, and the rear end of said firing pin is engageable by pivotal movement of said striker when released by the trigger mechanism to immediately cause the forward end of said pin to strike the percussion cap and detonate the propellant charge.

3. A fire extinguishing pistol as defined in claim 1, wherein said double swaging at the muzzle end of the barrel forms an annular recess backed by an internal

shoulder, and said sealing element is composite and sealed into said recess to form an air tight joint.

4. A fire extinguishing pistol as defined in claim 1, wherein said sealing element comprises two discs of card, a layer of plastic compound located between said discs, and a covering of thin metal foil applied to the outer disc.

5. A fire extinguishing pistol as defined in claim 1, wherein the fire extinguishing powder is a compressible and non-caking powder to act as a cushion to prevent settling of the fire extinguishing powder and to act as an expansion chamber for the propellant gases during discharge.

6. In a fire extinguishing pistol having a butt to receive a barrel for enclosing a cartridge containing a fire extinguishing preparation, a propellant charge and a detonator therefor, a disc of asbestos sheet disposed between the propellant charge and the fire extinguishing preparation, said disc being slotted to enable it to open under pressure

and ensure the full effect of the propellant gases being exerted centrally to cause discharge of the extinguishing preparation, means for detachably connecting the barrel to the butt of the pistol for re-charging the barrel, trigger mechanism, a spring-propelled pivotally movable striker releasable by the operation of the trigger mechanism to detonate the propellant charge and eject the contents of the cartridge, a firing pin mounted separately from said striker directly engageable and longitudinally movable by the striker, the rear end of said butt having an aperture about the firing pin, a bushing at the rear end of the barrel about said aperture and extending toward said striker and cooperative with the firing pin to seal the rear end of the barrel and said aperture to prevent rearward escape of pressure created by explosion of the propellant charge, a double swaging at the muzzle end of the barrel, and a sealing element having a fluid tight engagement with said swaging to prevent deterioration of the fire extinguishing preparation contained in the cartridge.
